UNITED STATES PATENT OFFICE.

DWIGHT S. RICHARDSON, OF NEW YORK, N. Y.

DESIGN FOR A GRATE-BAR.

SPECIFICATION forming part of Design No. 29,927, dated January 3, 1899.

Application filed December 9, 1898. Serial No. 698,788. Term of patent 14 years.

To all whom it may concern:

Be it known that I, DWIGHT S. RICHARDSON, residing in the city, county, and State of New York, have invented and produced a new and original Design for Grate-Bars, of which the following is a specification, reference being had to the accompanying drawings, forming a part thereof.

In said drawings, Figures 1 and 2 are elevations from different points of view of a grate-bar embodying my present design. Fig. 3 is a cross-section on the line $x-x$. Fig. 4 is a cross-section on the line $y-y$.

Like letters of reference indicate the same parts in all the figures.

The leading features of the present design are the plain faces of the triangular grate-bar, with transverse openings extending through the bar from face to face and transverse ribs on the faces intermediate the transverse openings.

A indicates the faces of the grate-bar triangularly disposed with relation to each other, giving the bar a triangular form in cross-section, as shown in Figs. 3 and 4.

25

B are the transverse openings in each face extending through to each of the other faces, and C are ribs extending transversely across the faces between the openings B and forming projections extending above the general plane of the faces, as shown clearly in Fig. 1.

30

The design is applicable to grate-bars for fuel-burners generally.

Having thus described my invention, what I claim as new, and desire to secure by Letters 35 Patent, is—

The design for a grate-bar herein shown and described.

DWIGHT S. RICHARDSON.
